DESIGN FOR A GASOLINE DISPENSING NOZZLE

Frederick E. Neef, Jr., United States Army,
Dundalk, Md.

Application December 15, 1941, Serial No. 104,646

Term of patent 3½ years

To all whom it may concern:

Be it known that I, Second Lieutenant Frederick E. Neef, Junior, United States Army, a citizen of the United States, residing at Dundalk, Maryland, have invented a new, original, and ornamental Design for a Gasoline Dispensing Nozzle, of which the following is a specification, reference being had to the accompanying drawing, forming part thereof.

The figure is a side elevational view of a gasoline dispensing nozzle, showing my new design.

The dominant feature of the design resides in the disk member with the beveled edge at the base of the nozzle spout as shown.

I claim:

The ornamental design for a gasoline dispensing nozzle, as shown and described.

FREDERICK E. NEEF, JR.
